UNITED STATES PATENT OFFICE.

LEWIS DODGE AND CHARLIE B. DODGE, OF MORSE BLUFF, NEBRASKA.

PNEUMATIC FOOT.

1,352,942.

Specification of Letters Patent. Patented Sept. 14, 1920.

Application filed October 6, 1919. Serial No. 328,832.

To all whom it may concern:

Be it known that we, LEWIS DODGE and CHARLIE B. DODGE, citizens of the United States, residing at Morse Bluff, in the county 5 of Saunders and State of Nebraska, have invented certain new and useful Improvements in Pneumatic Feet, of which the following is a specification.

This invention relates to improvements in 10 artificial feet and means for so arranging said artificial foot inside the boot or shoe that when in use, it will simulate the action of the human foot.

The type of artificial foot in general use 15 has been made usually of solid rubber, or of rubber having a hollow central portion or partially of rubber and some other material such as leather, canvas, etc.

Such devices, while a great improvement 20 upon the older structures made principally of wood or metal or of a combination of the two, nevertheless fail to a very large extent to furnish the proper degree of resiliency under the heel, and under the ball 25 and toes of the foot, when in use.

The object of our invention is to provide a durable, a practical and an inexpensive 30 artificial pneumatic foot, whose ease of operation and smoothness of action are such that the wearer will experience little or no jar or 35 discomfort to the leg or body when he throws his weight upon the foot in the act of walking.

With these and other objects in view, 40 which may be incident to the use of the improvements, the invention consists in the parts and combinations thereof hereinafter set forth and claimed, with the understanding that the several necessary elements constituting the same may be varied in proportions and arrangement without departing 45 from the nature and scope of the invention.

In order to make the invention more 50 clearly understood, there are shown, in the accompanying drawings, means for carrying the same into practical effect without limiting the improvements in their useful applications to the particular constructions, which, 55 for the purpose of explanation, have been made the subject of illustration.

In said drawings,

Figure 1 is a vertical sectional view of our 55 pneumatic foot, and Fig. 2 is a detail plan view of the bottom of the foot, a portion of the covering being

removed so as more clearly to show the arrangement of the wires or springs embedded therein.

Similar reference characters designate 60 like parts or features in the several figures of the drawings.

Referring to Fig. 1, the letter A shows the lower portion of an artificial leg, to the end B of which is attached in any suitable manner, the upper portion of our artificial foot, said foot consisting of two parts, namely the outer covering or casing 1, made of rubber fabric in which is embedded spring steel strips or bands 4, as more clearly shown in 70 Fig. 2, the purpose of which is to make the structure strong and durable and at the same time to assist in giving a spring-like motion to the foot when the same is in use in the act of walking. 75

Both leather and canvas have been found in practice to be unsuitable as an outer covering or casing, but rubber fabric, such as used in automobile tires, although of somewhat lighter texture, has proved very 80 satisfactory.

Referring again to Fig. 1, it will be noted that the steel strips or bands 4, begin at a point slightly above the opening 5, over the instep, continue down to and over the 85 toe 6, curving backwardly into the sole 7 throughout its length to the rear of the foot where they curve upwardly into the heel 8, terminating at a point about an inch or so 90 above the sole.

The rubber fabric in which the steel springs are embedded, while of strong and durable construction, is however, made with a due regard to the comfort of the wearer, and in varying degrees of thickness, a casing 95 for a man of heavy weight requiring a stronger and heavier construction than one for a man of medium or light weight.

That portion of the casing over the instep is cut at 5, as heretofore referred to, so as to 100 permit of the insertion of the inner tube or bladder 3, and laces and eyelets or hooks 9, are provided along the edges of said opening in the casing at that point so that it may be tightly laced, after the inner tube or bladder 105 is in place.

At a point opposite the opening 5, in the outer casing 4, said inner tube is provided with a metal tube 10, having a valve located therein and a screw cap 11, the construction of which is similar to those in use upon the inner tubes of automobile tires, so 110

as to permit of the proper inflation of said inner tube or bladder, when necessary.

Claims.

1. In an artificial foot, the combination with an outer casing of rubber or rubber fabric substantially of the shape of the human foot, having an opening therein for the insertion of an inner tube, of an inner tube of soft rubber substantially of the configuration of the outer casing adapted to fit within the latter and means which will permit of the inflation of said inner tube.
2. In an artificial foot, the combination with an outer casing of rubber or rubber fabric substantially of the shape of the human foot, having an opening therein over the instep, for the insertion of an inner tube, of an inner tube of soft rubber substantially of the configuration of the outer casing adapted to fit within the latter, and means which will permit of the inflation of the inner tube.
3. In an artificial foot, the combination with an outer casing of rubber or rubber

fabric substantially of the shape of the human foot, having an opening therein over the instep, for the insertion of an inner tube, of an inner tube of soft rubber substantially of the configuration of the outer casing adapted to fit within the latter, and a tube and valve attached to said inner tube which will permit of its inflation.

4. In an artificial foot, the combination with the outer casing of rubber or rubber fabric substantially of the shape of the human foot having steel strips embedded therein from a point above the toe to the heel and an opening for the insertion of an inner tube, of an inner tube of soft rubber substantially of the configuration of the outer casing, adapted to fit within the latter and means which will permit of the inflation of the inner tube.

In testimony whereof we affix our signatures.

LEWIS DODGE.
CHARLIE B. DODGE.
